UNITED STATES PATENT OFFICE.

SETH A. CRONE, OF EAST ORANGE, NEW JERSEY.

PIN OR BOLT RETAINER FOR RAILWAY-BRAKE-BEAM LEVERS AND CONNECTIONS.

Application filed October 13, 1924. Serial No. 743,429.

To all whom it may concern:

Be it known that I, SETH A. CRONE, a citizen of the United States, and resident of East Orange, in the county of Essex and State of New Jersey, have invented certain new and useful Improvements in Pin or Bolt Retainers for Railway-Brake-Beam Levers and Connections, of which the following is a specification.

The invention resides in a special retaining device for preventing the loss of a pin from a car brake rigging in the event that the usual cotter key customarily employed for securing the pin should have been inadvertently omitted or, if applied, should become broken or detached from the pin.

I illustrate my invention herein as applied to a brake beam strut and to the head of the usual pin on which the brake lever is mounted between the sides of the strut. The retaining device is formed from a flat piece of steel having a base section interposed between one side of the strut and the brake lever and having a hole through which the brake lever pin passes, and sections extending from the ends of said base section and adapted to be folded against the side edges of the strut side and inwardly toward each other over the head of the pin, thereby forming a box-band transversely encompassing a portion of the strut side and enclosing the head of the pin, the device thus being capable of retaining the pin in place regardless of the presence or absence of the cotter key.

The body of the retaining device is initially formed with bends or fold lines defining the several sections of the device, the device then having the sections thereof standing at various angles to one another, but being sufficiently open to permit of the insertion of the device between the strut sides and the placing of the perforated middle or base section thereof transversely against the inner face of the strut side the device is finally to encompass. The said bends define fold lines on which the several sections of the device are to be folded into box-band form. The sections defined by the bend or fold lines are definitely proportioned to the width and thickness of the strut side, plus the thickness of the head of the pin, and the device by reason of said bend or fold lines may be conveniently and with precision applied to operative position.

The invention will be fully understood from the detailed description hereinafter presented, reference being had to the accompanying drawings, in which:

Fig. 1 is a top view, partly broken away, of a trussed brake-beam, to the brake lever pin of which is applied the retaining device of my invention;

Fig. 2 is a section through the same, on a larger scale, taken on the dotted line 2—2 of Fig. 1; and

Fig. 3 is a perspective view of the retaining device in the form in which the same will be manufactured and sold, the device then being in condition to be properly applied along the fold lines indicated thereon to operative position.

In the drawings, referring to Figs. 1, 2 and 3, 10 designates a portion of a truss-brake beam having a compression member 11, a tension member 12, a strut 13 and the usual brake-lever 14 which extends between the sides 15, 16 of the strut and is secured by the usual brake lever pin 17, said pin having a head 18 at one end and a cotter key 19 at the other end. The sides 15, 16 of the strut are formed with the usual bosses 20 around the holes 21 therein for the brake lever pin.

The retaining device of my invention is numbered, as a whole, 22 and its purpose is to prevent the loss of the pin 17 in the event that the cotter key 19 should become broken or lose its place or should originally have been inadvertently omitted from the pin. The retaining device 22 is formed from a strip of mild steel and is given the initial form illustrated by solid lines in Fig. 3 and by dotted lines in Fig. 2, and said strip when in final operative position forms a box-like band, as shown in Fig. 2. The strip of steel from which the retaining device is formed is of suitable length and width, and said device comprises a middle portion or base section 23 somewhat greater in length than the width of the side member 16 of the strut and containing a hole 9 slightly larger than the hole 21 in said member 16, two corresponding end sections 24, 25 extending at angles from the ends of the base section 23 and having a length equal to or somewhat greater than the combined thickness of the strut side 16, boss 20 thereon and head 18 of the pin, a section 26 extending from the outer end of the section 24 and being of sufficient length,

by preference, to extend entirely across the head of the pin and nearly to the opposite edge of the retaining device and a section 27 extending inwardly from the outer end 5 of the section 25 and adapted to lap upon the outer end of the section 26, which is considerably longer than the section 27, as shown in Fig. 2.

In first applying the retaining device 22 to position, said device then being of the shape indicated by dotted lines in Fig. 2 and solid lines in Fig. 3, the device will be inserted endwise between the sides 15, 16 of the strut and the base member or section 23 of the retaining device will be moved against the inner face of the strut side 16 or to the position shown in Fig. 2. After the device has been applied to the position shown by dotted lines in Fig. 2, the brake lever 14 will be introduced between the strut sides 15, 16 and the brake lever pin inserted through said strut sides, at the holes 21 therein, and through the hole 9 in the base section 23 of the retaining device and 25 through the usual hole in the brake lever, and thereafter the sections 24, 25 will be bent outwardly against the side edges of the strut side 16 and thereupon the long outer section 26 of the retaining device will be 30 bent inwardly across the head 18 of the brake lever pin, after which the short section 27 of the retaining device will be bent inwardly to lap upon the outer end of the section 26, the whole then forming a box-like band transversely encompassing the strut side, the boss 20 thereon and the head of the pin 17, as clearly shown in Fig. 2. There is an advantage in having the section 26 of the retaining device of considerable 35 length, since thereby said section may be more readily bent inwardly across the head of the pin. There is also an advantage in having the section 27 of the retaining device comparatively short, since thereby said section is stiffened and may be used as a satisfactory lock or means for securing the outer end of the longer section 26 against the head of the pin. The section 27 being short, resists any tendency of the pin or other object 40 to turn it outwardly or bend it from the section 26, and hence the section 27 is in the nature of a strong lock for binding the section 26 against the head of the pin. When the retaining device is in its final position shown in Fig. 2 it will be obvious that the pin 17 cannot escape from the strut or brake lever regardless of whether the cotter key 19 is present or absent. It is also obvious that the retaining device being of box-like form 45 will not by any ordinary accident be torn from its operative position against the head of the pin 17, and to accomplish this purpose is one of the objects of my invention.

A distinguishing characteristic of my invention is that the retaining device is in the

form of a box-like closed or substantially closed band transversely encompassing the strut side 16 and the head 18 of the pin 17. A further characteristic of my invention resides in the fact that the retaining device 50 is formed in sections defined by bends or fold lines properly positioned to assure the convenient and correct application of the device to use. The device while made of mild sheet steel, as the metal is ordinarily 55 termed, is of material rigidity, and the bend or fold lines being properly positioned add very greatly to the convenient application of the device to the parts for which they are intended. A distinctive feature of the construction shown in Fig. 2 resides in the fact that the outer or top section 26 is of considerable length for convenience in the manipulation of the same and that the outer or top section 27 is short and stiff and adapted 60 for locking the section 26 in operative position.

I have described the invention as applied to brake-lever pins; but I do not confine the invention to the application of the retaining device to the strut for a brake-lever, since there are other connections in which the retaining device may be used in exactly the manner represented in Fig. 2 and hereinbefore described. The mechanism to which the retaining device will be applied will always comprise two parts having holes in register and a headed pin inserted through said holes for connecting said parts in free face to face relation, and the retaining device will have its middle or base section 65 interposed between said two parts and contain a hole through which said pin will pass, said device also comprising end sections extending outwardly from the ends of said 70 base section and outer sections extending from the outer ends of said end sections and to be folded toward each other over the head of the pin.

What I claim as my invention and desire 75 to secure by Letters Patent, is:

1. A pin or bolt retaining device of the character described for brake levers and the like comprising two parts having holes in register and a headed pin inserted 80 through said holes for connecting said parts in free face-to-face relation, in combination, said retaining device for said pin being of sheet metal and comprising a middle or base section interposed between said parts and having a hole through which said pin passes, end sections extending outwardly from the ends of said base section and outer sections extending from the outer 85 ends of said end sections and adapted to be folded toward each other at the outer face of the head of the pin, said device forming a box-like band encompassing one of said parts and the head of the pin, and one of said outer sections being materially 90

longer than the other outer section, which overlaps the outer end of said longer section, for the purpose described.

2. A pin or bolt retaining device of the character described for brake levers and the like comprising two parts having holes in register and a headed pin inserted through said holes for connecting said parts in free face-to-face relation, in combination, said retaining device for said pin being of sheet metal and comprising a middle or base section interposed between said parts and having a hole through which said pin passes, end sections extending outwardly from the ends of said base section and outer sections extending from the outer ends of said end sections and adapted to be folded toward each other at the outer face of the head of the pin, said device forming a box-like band encompassing one of said parts and the head of the pin, and one of said outer sections being of such length as to extend entirely across and beyond the head of the pin, while the other outer section is short and overlaps the outer end of said first-mentioned outer section.

3. In a brake-beam having a strut formed with opposite sides and a brake lever pivoted between said sides on a headed pin extending through holes in said sides and lever, a sheet metal retaining device for said pin comprising a middle or base section interposed between said lever and one of said sides and having a hole through which said pin passes, end sections extending outwardly from the ends of said base section and along the side edges of said strut side and outer sections extending inwardly over the head of the pin from the outer ends of said end sections, said device forming a box-like band transversely encompassing said strut side and the head of the pin, and one of said outer sections being materially longer than the other outer section, which overlaps the outer end of said longer section, for the purpose described.

Signed at New York city, in the county of New York and State of New York, this 9th day of October A. D. 1924.

SETH A. CRONE.
